(57) **CLAIM**

The ornamental design for a fin plug assembly for a surfcraft, as shown and described.

DESCRIPTION

FIG. 1 is a top view of a fin plug assembly for a surfcraft; FIG. 2 is a first end view thereof;

FIG. 3 is a first side view thereof;

FIG. 4 is a bottom view thereof;

FIG. 5 is a second end view thereof;

FIG. 6 is a second side view thereof; and,

FIG. 7 is an upper perspective thereof.

The broken line showing the center opening of the fin plug assembly for a surfcraft is included for the purpose of illustrating portions of the “article” and forms no part of the claimed design.
